TRAFFIC MARKER ROD

Harry T. Thompson, Hollywood, Calif.

Application November 6, 1940, Serial No. 364,595

5 Claims. (Cl. 91—62.5)

My invention relates to a traffic marker rod and has for its principal object, the provision of a relatively simple, practical and inexpensive device to be used by traffic officers for the convenient marking of the tires of parked automobiles, which marking serves as a guide for indicating the parking time of the car and consequently assisting materially in the control of traffic.

In practically all cities or wherever motor vehicle traffic is more or less congested, there are ordinances governing the time limit for the parking of motor vehicles and where such conditions exist it is the general practice of traffic officers mounted on motorcycles to drive along the streets or highways and with a piece of chalk or the like mark the tires of parked motor vehicles and which markings enable the officer patrolling the street or highway to determine whether or not the marked vehicles are parked over time or beyond the periods permitted by the traffic laws.

Tire marking devices now in use embody rods or sticks carrying at their distal ends pieces of chalk or crayon which, as the traffic officer drives past a parked car, is brought into contact with the tread surface of the wheel of a parked car, but such practice is unsatisfactory for the reason that the officer must slacken speed each time a tire is marked and there is always the attendant danger of breaking the chalk or crayon during the marking operations.

It is the principal object of my invention to provide improved means including a hollow rod perforated at its distal end and containing powdered or pulverized chalk or the like, a small portion of which latter is discharged from the perforations at the end of the rod and delivered directly onto the tread portion of a tire and which provision enables the wheels of parked cars to be marked with a considerable saving of time as compared to the present marking methods and further, by using pulverized material as the marking medium there is no loss of substantial portions of such medium due to breakage or crumbling of crayon or chalk at the time the same is drawn across the surface of a tire to mark same.

With the foregoing and other objects in view, my invention consists in certain novel features of construction and arrangement of parts that will be hereinafter more fully described and claimed and illustrated in the accompanying drawing in which:

Fig. 1 is a perspective view showing a traffic

marker rod as the same appears while in use.

Fig. 2 is an elevational view of the rod with the end portions thereof in longitudinal section.

Fig. 3 is an enlarged cross section taken on the line 3—3 of Fig. 2.

Fig. 4 is a perspective view of the cartridge that contains the marking powder and which is inserted in the upper portion of the marking rod.

Referring by numerals to the accompanying drawing which illustrates a preferred embodiment of my invention, 10 designates a tube, preferably of metal, and which for all practical purposes may have a length of two or three feet and a diameter of a half inch, more or less.

Secured to one end of this tube is a slightly larger tube 11 which may have a length of from eight to twelve inches and removably applied to the upper end of this larger tube 11 is a closure 12, preferably a screw cap.

Secured in any suitable manner, preferably by means of an adhesive, to the upper portion of tube 11 immediately below cap 12, is a sheath 13 of leather, rubber, or analogous material, and which provides a more or less flexible gripping surface for the hand of the user of the marking device.

The elongated chamber 14 in tube 11 is adapted to receive a cartridge or container C formed of thin, flexible material such as paper and which is filled with powdered chalk.

The length of this cartridge or container is approximately equal to or slightly less than the chamber 14 in tube 11 so that when the cartridge is inserted in said tube its lower end will rest on the shoulder at the lower end of chamber 14 and which shoulder is formed by the upper end of tube 10. Prior to the insertion of the chalk-containing cartridge into the chamber 14, the lower end of said cartridge is punctured or torn away so as to permit the powdered chalk to flow readily from the cartridge or container downwardly through tube 10.

The lower end of tube 10 is closed in any suitable manner and formed in said closed lower end and in the wall of the tube adjacent said closed end are apertures 15 which permit the chalk to discharge from the lower end of the device, and applied to tube 10 and covering the lower perforated one thereof is one or more sleeves 16 of loosely woven fabric. While this fabric permits the passage of a certain amount of the pulverized chalk when the same is forcibly expelled through the apertures 15, it normally prevents the free flow or discharge of the powder through the apertures 15.

The marking rod is made ready for use by removing cap 12, inserting a cartridge containing pulverized chalk into the chamber 14 in tube 11 with the lower end of said cartridge punctured or torn away to permit the powdered chalk to flow freely downwardly into tube 10. The wrapper of the cartridge remains in chamber 14 as the lower end of said cartridge rests on a shoulder formed by the upper end of tube 10, so that said wrapper may be readily removed when the marker is subsequently charged with a filled cartridge.

As the traffic officer rides past a parked car that is to be marked so as to aid the officer in determining the length of time that the car is parked, the rod is "stabbed" toward one of the tires of the car and when the distal end of the marker strikes against the tire a small amount of powdered chalk will be forcibly expelled through the apertures 15 in the lower end of tube 10 and through the interstices of the fabric covering 16, thus leaving a definite mark on the tire.

It is the practice of traffic officers in checking parked cars to make regularly timed trips along the streets and highways where the cars are parked and thus by noting the marked tires, the officer may readily check those cars that are parked over time.

Thus it will be seen that I have provided a traffic marking device that is relatively simple in construction, inexpensive of manufacture and very effective in performing the functions for which it is intended.

It will be understood that minor changes in the size, form and construction of the various parts of my improved traffic marker rod, may be made and substituted for those herein shown and

described, without departing from the spirit of my invention, the scope of which is set forth in the appended claims.

I claim as my invention:

- 5 1. A traffic marking device comprising a rod provided in its upper portion with a chamber, a cap removably positioned on the upper end of said rod and closing the upper end of said chamber, the lower portion of the rod being provided with a duct that leads downwardly from said chamber, the chamber in said rod being adapted to receive a body of pulverized marking material and the distal end of the rod being provided with perforations that communicate with the lower end of the duct in the lower portion of said rod.
- 10 15 2. A traffic marking device as set forth in claim 1 and with a sleeve of reticulated material covering the perforated end of the rod.
- 20 25 3. A traffic marking device comprising an elongated hollow member adapted to receive pulverized marking material, the distal end of said member being provided with perforations that communicate with the chamber within said member, a screen surrounding the perforated end of said member and a sleeve of flexible material mounted on the upper portion of said member to provide a gripping surface.
- 30 35 4. A traffic marking device comprising a tubular member, the upper portion thereof being constructed to receive a cartridge containing pulverized marking material, means for supporting the wrapper of said cartridge in the upper portion of said member and the lower end of the wall of said member being perforated.
5. A traffic marking device as set forth in claim 4 and with a flexible screen surrounding the perforated portion of said member.

HARRY T. THOMPSON.
